FLUORESCENT LAMP APPLYING MEANS

Edwin G. Gaynor, Fairfield, and Harold K. Andrews, Stratford, Conn.; said Andrews assignor to said Gaynor

Application September 27, 1943, Serial No. 503,912

18 Claims. (Cl. 294—20)

This invention relates to new and useful improvements in fluorescent lighting equipment and has particular relation to a combination including a fluorescent lamp which may be applied to a fixture by a simple rectilinear movement and a manually operable extension means for applying such lamp to a fixture located high above a floor or in any other place not readily accessible, and the invention is also especially concerned with such extension means per se.

The objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a side elevational view showing my extension means supporting a fluorescent lamp in a predetermined relation to a fixture and just prior to actuation to apply such lamp to the fixture;

Fig. 2 is an end elevational view of the extension means, the view being on a larger scale and with a portion broken away;

Fig. 3 is a top plan view of the extension means alone;

Fig. 4 is a longitudinal sectional view through the extension means of the invention, the view being taken as along the plane of the line 4—4 of Fig. 3;

Fig. 5 is a sectional view taken as along the plane of the line 5—5 of Fig. 1 on a larger scale;

Fig. 6 is a view partly in side elevation and partly in section of one end portion of my extension and showing the parts in the position to which they have been actuated to apply a lamp to a fixture;

Fig. 7 is a sectional view taken as along the plane of the line 7—7 of Fig. 4;

Fig. 8 is a sectional view taken as along the plane of the line 8—8 of Fig. 6;

Fig. 9 is a sectional view taken as along the plane of the line 9—9 of Fig. 4; and

Fig. 10 is a perspective view of one of the carriers employed.

Referring in detail to the drawings at 10 is shown a fixture having mounted thereon the base portion 11 and 12 of the two part fluorescent lamp sockets 13 and 14 respectively. The plug portions 15 and 16 of the respective sockets receive the usual end contact pins of a fluorescent lamp 17 and are adapted to have their prongs 18 and 19 inserted into the base portions 11 and 12 into engagement with contacts therein to mount the lamp 17 on the fixture 10 and to electrically connect the lamp for control as by a switch 20 located on the fixture 10 or otherwise as may be convenient.

The lamp 17 having the socket plug portions 15 and 16 assembled thereon is adapted to be mounted on the fixture 10 by a simple rectilinear motion. The details of the sockets 13 and 14 and the relation of their parts to one another and to the lamp are fully disclosed in my copending application, Serial Number 504,596, filed October 1, 1943. According to the invention the lamp may be applied to the socket by an extension means generally designated 21 and the latter includes a head generally designated 22 and a handle 23 which latter is for manipulation of the head and may be of one length or which may include sections for varying its length or which may be detachably mounted on or attached to the head for changes of handles to provide handles of different lengths as desired. In addition where the head and handle are detachably connected this provides for the attachment, to the one handle, of heads of various sizes.

As herein disclosed, head 22 includes a tubular bar or element 24 having a strap 25 partly wrapped about its mid-portion. The ends of the strap 25 are located below the bar 24 and are bent to form a tubular socket portion 26 receiving the upper or inner end portion of the handle 23 which is also shown as a tubular member. A screw or the like 27 detachably secures the handle 23 to the head 22. A cross-pin 28 passes through the strap 25 and the mid-portion of bar 24 and locks these parts together and in addition forms a shaft mounting a pair of pulleys 29 and 30 for a purpose to be set forth. The mentioned pulleys are shown as of such diameter as to extend partly into the upper part of tubular portion 26, a slot 31 being provided in the under side of the mid-portion of bar 24 for the accommodation of the pulleys.

On each end portion of the bar 24 is a mounting means comprising a metal strip bent upon itself to provide a narrow U-shaped portion 32 disposed below the bar and intermediate portions 33 and 34 disposed against the under and outer sides of such bar and fastened to the latter as by screws 35. Above the bar 24 the side arms of such strip are bent to extend outwardly or away from one another as at 36 and 37 and then upwardly as at 38 and 39.

Such mounting means is of the same construction at each end of bar 24 and each mounting means supports or mounts a guide. The guides 45 are of the same construction but for the purpose of aiding in further description have been numbered 40 and 41, respectively, at the different ends of the bar 24. Guides 40 and 41 have open sides facing one another and in addition the guides 55 are open at their outer ends. Thus each guide 60 is open at its outer ends.

includes an outer wall 42, a relatively long edge wall 43 and a shorter edge wall 44.

The lower ends of the edge walls of the guides are disposed on the outwardly directed portions 36 and 37 of the mounting means and rivets or other securing means 45 serve to secure such walls to the upstanding portions 38 and 39 of said mounting means. Wall 42 of each guide has a slot 46 opening through the lower or inner edge thereof. Mounted in the guides 40 and 41 are carrier 47 and 48 respectively (of identical construction but separately numbered for the purpose of further description).

Carrier 47 is shown alone in Fig. 10 and there it will be noted that the same includes a bottom wall 49, an outer or rear wall 50 and side walls 51. A perforated ear 52 is secured to the underside of the carrier in any suitable manner and may in fact be formed by lancing and pressing a piece from the bottom wall 49 of the carrier.

The carriers 47 and 48 are shiftable in the guides toward and from the open outer or upper ends of the latter. Edge walls 43 and 44 of the guides have their forward edges bent inwardly to provide flanges 53 located parallel with the rear walls 42 of the respective guides. Thus when the carriers are located in the guides their movements toward and from the open upper ends of the guides are controlled and guided by the side walls 43 and 44, rear walls 42 and the flanges 53.

Toggle means are provided for shifting the carriers in their respective guides. Thus toggle 54 is associated with carrier 47 and a similar or identical toggle 55 is associated with carrier 48. Each toggle includes a lower link 56 having its lower end located between the arms of the bent portion 32 of its mounting means and anchored by a pivot pin 57. Upper link 58 of each toggle is pivoted at its upper end to the ear 52 of its carrier as by a pin 59.

An operating link 60 of each toggle is pivotally connected at its outer end with the upper end of link 56 and the lower end of link 58 by a pin 61. Slots 62 and 63 may be provided in the end portions of the bar 24 through the upper and lower portions thereof for the accommodation of the various links of the toggles. A spring 64 is associated with each toggle 54 and 55 and each such spring has an arm 65 bearing against a toggle link 56 and an arm portion 66 hooked over the inner end wall of a slot 63. With this arrangement it will be clear that the springs constantly tend to maintain the toggles in broken or folded condition and to move them back to such condition when moved therefrom and then released.

Connected with the inner ends of the toggle operating links 60 are ropes or heavy cords 67 and 68 respectively carried toward one another through the tubular bar 24 and after passing over pulleys 30 and 29 respectively passing downwardly through the handle 23 and out through the lower end thereof. These ropes provide means for operating the toggles to straighten their links relatively and thus shift the carriers 47 and 48 toward the upper ends of the respective guides. On release of the ropes the springs 64 return the toggles to their normal conditions simultaneously drawing the carriers back to their normal positions.

While the arrangements may be such that the ropes operate the toggles to or even through a dead-center position it is preferred that the movement stop short of dead-center when the device is being used to mount lamp 17 on fixture

10. When the arrangements are as described there is a slight reserve motion available to give the lamp and its end socket portions an extra movement when such may be made necessary by 5 a variation in the size of any parts employed. Further when the toggles are not actuated to a dead-center position the springs 64 may function to return the toggles and the carriers to their normal position.

Carried by the bar 24 and fixed in predetermined relation thereto and to the guides 40 and 41 are a pair of locating or aligning pins 69 and 70. These pins are mounted as by straps 71 bent about the bar and having their end portions 72 perforated and arranged in close parallel relation. Screws 73 passing through such perforated end portions are threaded into the lower ends of the pins and on being tightened cause the strap to grip the bar and in addition 20 attach the pins to the straps and thus the bar. Preferably each pin 69 and 70 toward its outer end is pointed or bullet-shaped as a 74 and inwardly of such end is notched to provide an inwardly facing shoulder 75.

25. Socket bases 11 and 12 are mounted on the bottom or inner wall of the fixture 10 and each base includes a neck portion 76 passing through such wall and having openings therein for the reception of the contact prongs 18 and 19 of the 30 plugs 15 and 16. The mentioned wall of the fixture is designated 77 and in such wall are 35 a pair of holes 78 spaced apart as are the pins 69 and 70 and bearing approximately the same relation to the entrances to the bases 11 and 12 as do the pins 69 and 70 to the prongs 18 and 19 of the plugs 15 and 16 when the latter are located in the carriers 47 and 48.

40. Thus when lamp 17 is to be mounted on fixture 10 the plugs 15 and 16 are mounted on the 45 respective ends of the lamp. Thereafter such plugs are disposed in the carriers 47 and 48 with the lamp now supported by the plugs and carriers as shown in Fig. 1. At this time the carriers are in their lower or retracted positions. Now the extension means is raised and the ends of the pins 69 and 70 introduced through the holes 78 in wall 77 of the fixture. A slight lateral movement of the extension hooks the shoulders 75 on the pins over the edges of the holes as 50 shown in Fig. 5. Now the prongs 18 and 19 are aligned with the entrance openings to the bases 11 and 12.

55. The operator straightens the toggles, as by pulling the ropes 67 and 68, and the carriers 47 and 48 are shifted upwardly in the guides causing the prongs of the plugs to enter the bases 11 and 12. The shoulders 75 of the pins 69 and 70 being hooked over the bottom wall of the fixture the parts do not move downwardly as the ropes are pulled and so the carriers are moved upwardly moving the contact prongs into the bases of the sockets. Only a simple rectilinear movement of the carriers and the socketed lamp is involved.

60. When the prongs are home the extension means is given a slight lateral movement to take pin shoulders 75 off the wall 77 of the fixture whereupon the entire extension means may be 65 lowered leaving the lamp mounted on the fixture. The described lateral movement of the extension means would be toward the right as the device is viewed in Fig. 5 although at the described time the parts would have been moved to the positions of Fig. 6 and thereafter the car-

riars would have been moved back to their normal position by the springs 64.

Thus at the time of the described lateral movement of the extension means the carriers are in their lower or retracted positions and the open upper side edges of the guides 40 and 41, the portions above the short walls 44 comprising such open upper side edges, are opposite the edges of the plugs. Thus the extension may be shifted laterally leaving the plugs connected with the bases and supporting the lamp.

It will be understood that the device of the invention may be provided in various sizes to receive the various lengths of fluorescent lamps. The relationship of the parts is such that when the plugs are on the ends of a lamp such plugs may be received in the carriers 47 and 48 of the device. At the same time the bases are located in proper spaced relation to receive the contact prongs of the plugs and the pins 69 and 70 have such relation to each other and the holes 78 as to align the plug prongs with the entrances to the bases when such pins are located in the holes with the shoulders 75 of the pins in full engagement with the bottom wall of the fixture.

When the carriers have been retracted to their normal positions from the positions of Fig. 6 the plugs are connected with the bases and are not retracted and thus are left in position above the upper edges of the walls of the carriers so that the entire extension means may be moved laterally due to the provision of the short walls 44 of the guides and above which walls the plugs are located at the time of such lateral movement of the present extension means.

Having thus set forth the nature of our invention, what we claim is:

1. In an extension means of the class described, a head, a handle for manipulating said head, a pair of open ended guides on said head, a carrier in each of said guides and shiftable toward and from the open ends thereof, said carriers spaced to receive socketed ends of a tubular fluorescent lamp, and means operable from said handle to shift said carriers in one direction in said guides.

2. In an extension means of the class described, a head, a handle for manipulating said head, a pair of open ended guides on said head, a carrier in each of said guides and shiftable toward and from the open ends thereof, said carriers spaced to receive socketed ends of a tubular fluorescent lamp, means operable from said handle to shift said carriers in one direction in said guides, and spring means to shift said carriers in the opposite direction on release of said means operable from the handle.

3. In an extension means of the class described, a head, a handle for manipulating said head, a pair of open ended guides on said head, a carrier in each of said guides and shiftable toward and from the open end thereof, said carriers spaced to receive socketed ends of a tubular fluorescent lamp, locating means carried by said head for engagement with a lamp fixture to locate said head and carriers in predetermined relation to such fixture, and means operable from said handle to shift said carriers in one direction in said guides.

4. In an extension means of the class described, a head, a handle for manipulating said head, a pair of open ended guides on said head, a carrier in each of said guides and shiftable toward and from the open ends thereof, said carriers spaced to receive the socketed ends of a tubular flu-

orescent lamp, toggle means connected with each of said carriers, and means operable from said handle to actuate said toggle means to shift said carriers in one direction in said guides.

5. In an extension means of the class described, a head, a handle for manipulating said head, means on said head to receive the socketed end portions of a fluorescent lamp, means to shift said means to impart a rectilinear movement to said lamp, and means operable from said handle to shift the second named means and cause said movement of the lamp.

6. In an extension means of the class described, a head, a handle for manipulating said head, means on said head to receive the socketed end portions of a fluorescent lamp, movable means to shift said means to impart rectilinear movement to said lamp, means operable from said handle to move the second named means and cause said movement of the lamp, and said movable means including a toggle means for imparting such movement to said lamp and a spring means for imparting a return movement to such toggle means.

7. In an extension means of the class described, a head, a handle for manipulating said head, a pair of open ended guides on said head, a carrier in each of said guides and shiftable toward and from the open ends thereof, said carriers spaced to receive socketed ends of a tubular fluorescent lamp, means operable from said handle to shift said carriers in one direction in said guides, said guides each including side walls, and one of said side walls of each guide shorter than the other wall thereof and of a length not substantially greater than that of the stroke of the carrier of said guide.

8. In an extension means of the class described, a head, a handle for manipulating said head, a pair of open ended guides on said head, a carrier in each of said guides and shiftable toward and from the open end thereof, said carriers spaced to receive socketed ends of a tubular fluorescent lamp, locating pins carried by said head and having laterally extending shoulders for engagement with a lamp fixture to locate said head and carriers in predetermined relation to the fixture and maintain the head against movement away from the fixture, means operable from said handle to shift said carriers in one direction in said guides, said guides each including side walls, and the side wall of each guide on the side thereof toward which said shoulders of the locating pins extend being shorter than the other walls thereof and of a length not substantially greater than that of the stroke of the carrier of such guide.

9. In an extension device of the class described, a head comprising a tubular member, a handle for manipulating said head, said handle comprising a tubular member connected at its inner end with said head substantially mid-way the ends thereof and communicating through said end with the interior of the tubular member of the head, a pair of guides, means mounting said guides in spaced relation on the tubular member of the head at the side of the latter opposite said handle, said guides open at their outer ends, a carrier in each of said guides and movable therein toward and from the outer end thereof, and means operable through the tubular member of the head and said tubular handle from the outer end of the latter to move said carriers toward the outer ends of the guides.

10. In an extension device of the class de-

scribed a head comprising a tubular member, a handle for manipulating said head and comprising a tubular member connected at its inner end with the tubular member of the head substantially mid-way the length of the latter and communicating with the interior thereof, a pair of guides, means mounting said guides in spaced relation on the tubular member of the head at the side thereof opposite said handle, said guides open at their outer ends, a carrier in each of said guides and movable therein toward and from the outer end thereof, pivoted lever means connected with said carriers, and means operable from the outer end of said handle through the latter and said tubular member of the head to rock said pivoted lever means and move said carriers toward the outer ends of the guides.

11. In an extension device of the class described, a head comprising a tubular member, a handle for manipulating said head and comprising a tubular member connected at its inner end with the tubular member of the head substantially mid-way the length of the latter and communicating with the interior thereof, a pair of guides, means mounting said guides in spaced relation on the tubular member of the head at the side thereof opposite said handle, said guides open at their outer ends, a carrier in each of said guides and movable therein toward and from the outer end thereof, pivoted lever means connected with said carriers, and flexible cords operable from the outer end of said handle through the latter and said tubular member of the head to rock said pivoted lever means and move said carriers toward the outer ends of the guides.

12. In an extension device of the class described, a head comprising a tubular member, a handle for manipulating said head and comprising a tubular member connected at its inner end with the tubular member of the head substantially mid-way the length of the latter and communicating with the interior thereof, a pair of guides, means mounting said guides in spaced relation on the tubular member of the head at the side thereof opposite said handle, said guides open at their outer ends, a carrier in each of said guides and movable therein toward and from the outer end thereof, pivoted lever means connected with said carriers, and flexible cords operable from the outer end of said handle through the latter and said tubular member of the head to rock said pivoted lever means and move said carriers toward the outer ends of the guides, and spring means associated with each of said lever means and operable to shift them and move said carriers inwardly of said guides on release of said flexible cords.

13. In an extension means of the class described, a head, a handle for manipulating said head, a pair of spaced guides on said head and each open at its outer end, a carrier in each of said guides and movable toward and from the open end thereof, means to move said carriers in said guides, a pair of locating pins carried by said head and positioned laterally with respect to said guides, each of said guides including a long wall at one side and a short wall at its other side, and said guides having their short walls at their sides toward said locating pins.

14. In an extension device of the class described, a head, a handle for manipulating said head, a pair of guides, means mounting said guides in spaced relation on said head, said guides open at their outer ends, a carrier in each of said guides and movable therein toward and

from the outer end thereof, pivoted lever means, means connecting said lever means with said carriers, and means operable from the outer end of said handle to rock said pivoted lever means and move said carriers toward the outer ends of said guides.

15. In an extension device of the class described, a head comprising a tubular member, a handle for manipulating said head and comprising a tubular member connected at its inner end with the head substantially mid-way the length of the latter and communicating with the interior thereof, a pair of guides, means mounting said guides on the tubular member of the head at the side thereof opposite said handle, said guides open at their outer ends, a carrier in each of said guides and movable therein toward and from the outer end thereof, a pair of toggle means, means mounting said toggle means one on each end of said tubular member of the head with each toggle means connected with a carrier, an operating link connected with the mid portion of each of said toggle means and extending into the ends of the tubular member of the head, and means connected with the inner ends of said links and passing through the tubular members of the head and handle and operable from the inner end of the latter to actuate said toggle means and shift said carriers in one direction in said guides.

16. In an extension device of the class described, a head comprising an elongated member, a handle for manipulating said head, a pair of carriers, means mounting said carriers on said head for movement toward and from the latter, a pair of toggles mounted on said head and each connected with one of said carriers, and means operable from said handle to simultaneously actuate said toggles to shift said carriers in one of said directions.

17. In an extension device of the class described, a head comprising a tubular member, a handle for manipulating said head and comprising a tubular member connected at its inner end to the mid-portion of the head and communicating with the interior thereof, a pair of carriers, means mounting said carriers on said tubular member of the head for guided movements toward and from the latter, a pair of toggle means, means mounting said toggle means one on each end portion of said tubular member of the head with each toggle means connected to operate a carrier, and means connected with said toggle means and extending through the tubular members of the head and handle and operable from the inner end of the latter to actuate said toggle means and shift said carriers in one of said directions.

18. In an extension means of the class described, an elongated head, a handle for manipulating said head, a pair of guides on said head, a pair of carriers mounted by said guides for guided movements toward and from the head in directions transverse thereto, said carriers spaced to receive socketed ends of an elongated tubular fluorescent lamp with the latter arranged substantially parallel to said head, a pair of spaced locating means carried by said head and extending transversely thereof for engagement with a lamp fixture to locate the head and carriers in predetermined relation to such fixture, and means operable from said handle to shift said carriers in one direction relative to said head.

EDWIN G. GAYNOR.
HAROLD K. ANDREWS.
